ELECTRON DISCHARGE DEVICE MOUNT
SPACER

Don F. Holshouser, East Orange, N. J., assignor to
Radio Corporation of America, a corporation of
Delaware

Application February 9, 1943, Serial No. 475,239

6 Claims. (Cl. 250—27.5)

My invention relates to electron discharge devices and particularly to methods and means for supporting electrode structure within an enclosing envelope and to electrical contact means for such devices.

In many electron discharge devices it is necessary to mechanically support a relatively long electrode structure against transverse movement when subjected to shock or gravitational forces and it has been customary to provide spring fingers or metal strips affixed at one end of the electrode structure to be supported and bearing against the envelope wall at the opposite end or ends thereof. Such strips are resiliently deformed by stresses comprising both tension and compression in the strips, and such strips being subjected to the various baking and heating steps during tube manufacture suffer a loss in their resiliency whereupon their efficiency is impaired. Consequently, a great number of such strips such as eight to twelve separate strips may be required in an individual tube for adequate support. The inefficiency of such strips is particularly objectionable in discharge devices of the cathode ray type having a relatively massive electron gun and deflection plate structure supported within the neck section of the tube from the sealed or stem end.

It is an object of my invention to provide resilient support members or spacers for supporting electrode structures in electron discharge devices which will not become defective during manufacture or use of the devices. It is another object to provide a resilient electrical contact through which electrical connection may be made to electrode structure within a discharge tube. It is a further object to provide improved electrode mount supporting means which are easy to assemble, rugged in construction, inexpensive to manufacture and which at the same time provide adequate support for relatively massive electrode structures. In accordance with my invention, I provide one or more resilient spring members each affixed to a transverse support on the electrode mount assembly, preferably surrounding the transverse support and affixed thereto at a plurality of points, the resilient member or members being continuous around the support and having no free ends so that upon insertion of the mount assembly within a glass envelope or other container the resilient member or members are stressed in compression throughout the entire cross-section thereof, the compressive force being the sole force to center and support the electrode assembly in the envelope. In addition,

the resilient member or members may serve as electrical conductors to electrically connect electrodes within the envelope such as a conductive wall coating to one of the mount electrodes.

5 These and other objects, features and advantages of my invention will become apparent when viewed with respect to the following description and the accompanying drawing wherein:

10 Figure 1 is a longitudinal view of a discharge device of the cathode ray type incorporating my invention; and

Figure 2 is a perspective view of the electrode mount structure shown in Figure 1.

15 While I will describe my invention with particular reference to its application in cathode ray tubes, it will be appreciated that it is nevertheless equally applicable to other electron discharge devices where it is desirable or necessary to support the electrode structure from the bulb side walls. Referring to Figure 1, I have shown a cathode ray tube comprising an envelope, generally designated 1, having a neck section 2, a stem, not shown, closing one end of the neck section and supporting the electrode mount structure 3, the opposite end of the tube being provided with a screen or target 4 with a conductive wall coating 5 intermediate the stem and target. The mount structure 3 comprises conventional electron gun electrodes which it is desired to support within the neck section 2, the structure comprising more particularly a conventional centrally apertured grid 6 enclosing the usual cathode and heater (not shown), a cylindrical anode 7 and a plurality of apertured anode

20 discs 8, 9, 10 and 11. The anode 7 is supported from the stem such as by a plurality of ceramic rods 12 and the discs 8—11 are in turn supported from the anode 7 by additional ceramic rods 13 which may likewise be used to position and support conventional electrostatic deflection plate pairs 14—15. In accordance with the usual construction of such tubes, the anode discs 8—11 may be maintained at increasing positive potentials by connecting lead wires extending through the stem of the tube from the base member 16, it being customary to apply the highest potential to the anode disc nearest the target 4 such as the disc 11 and also to the conductive coating 5.

25 30 35 40 45 50 55 In accordance with my invention I provide a transverse member supported by the mount structure 3 such as the anode discs 10 or 11 and affix thereto a resilient mount support spacer 17 as best shown in Figure 2. I prefer to utilize two such mount support members 17 although one or

more may be sufficient depending upon the degree of support required for any particular application. The mount support spacer or spacers in accordance with my invention are continuous bands of resilient material such as thin metal striping affixed to the transverse mount support at a plurality of points such as at the points 18. I prefer to form the spacer or spacers 17 in the shape of a three-lobed heart cam contacting and affixed to the anode disc or discs at three 15 equally spaced points about the anode periphery so that the lobes of the mount spacer extend beyond the periphery of the anode and lie tangent to a circle concentric with the longitudinal axis of the mount assembly. Furthermore, I prefer to maintain the points of support of the spacer and the points of contact with the bulb wall coplanar so that no longitudinal stress is applied to the mount assembly. The mount spacer material may be of metal such as a nickel-chromium 20 alloy usually referred to as "Nichrome" or "Inconel" or other resilient material capable of retaining its resiliency upon heating to the temperatures usually reached during tube manufacture such as attained at bake-out temperatures of 300° to 500° C. Although I have shown the transverse support members 10 and 11 as being of circular shape, this is not at all necessary, the shape being determined merely by the other requirements of electrode structure. The only requirement is a plurality of preferably equally spaced points to which the spacer is affixed such as by welding, these points being at equal radial distances from the longitudinal axis of the electrode structure.

The spacer material may be of Nichrome strip having a thickness of from .002-.010" and a width of $\frac{1}{8}$ to $\frac{1}{4}$ ". This thickness and width is sufficient for proper rigidity of a mount structure such as contained in the commercial cathode ray tube type RCA 5CP1 when utilizing two such spacers as shown in the drawing. When utilizing two such spacers of equivalent dimensions in a uniform diameter envelope portion it is desirable to displace the points of contact which one spacer makes with the envelope with respect to the corresponding points of the other spacer so that these points are unaligned in an axial direction. When utilizing two three-lobed spacers the points of contact on the envelope wall are displaced one from the other by 30 degrees around the inner periphery of the envelope.

I choose the length of the material comprising the spacers 17 less than the inner circumference of the envelope wall at the eventual points of contact such that following shaping in the desired form and attachment to the transverse members at the plurality of points 18 the mount assembly may be forced into the neck 2 of the envelope 1 before the stem is sealed to the lower end of the neck section. Upon assembly in the envelope the lobes of the spacers are forced inwardly toward the mount axis stressing each portion of the spacer between the points of support on the transverse member wholly in compression. Such a mode of support is far more rigid for a given thickness and width of spacer material than for a spacer which has free ends bearing on the neck section of the envelope and wherein the stress in the spacer is a combination of tension and compression.

As a particular example, I have made tubes of the type described having a nominal internal

neck diameter of 1.86 inches and tolerances of ± 0.120 inch utilizing spacers having a total length surrounding the transverse members of 5.75 inches allowing an overlap at the ends of 5 0.020 inch. The unstressed spacer has a maximum radial dimension of 1.01 inches between the axis of the mount structure and each eventual point of contact with the bulb wall prior to assembly, this dimension being reduced to the radius of the bulb neck section following assembly. It will be noted from the drawing that I utilize the spacer 17 as an electrical contacting means between the anode disc 11 and the conductive wall coating 5, the three points of support combined with the fact that the spacer is wholly in compression providing excellent electrical contact to the coating 5 so that it may be operated at the same potential as the anode disc 11. To prevent abrasion of the coating 5, the spacer may have a slight rounded rib or embossed portion 19 to provide smooth engagement between the coating 5 and the spacer as the mount is slipped into the neck portion 2.

While I have described only one specific embodiment of my invention and have described its use with particular reference to a cathode ray tube, it will be appreciated that other modifications may be made and various uses contemplated without departing from the scope of my invention as set forth in the appended claims.

I claim:

1. An electron discharge device comprising an envelope having a tubular portion, an electrode structure within said tubular portion, a transverse member on said structure and a resilient envelope spacer completely surrounding said transverse member having points of contact with said envelope and affixed to said transverse member at points intermediate said points of contact.

2. An electron discharge device comprising an envelope having a tubular portion, an electrode mount structure within said tubular portion, a transverse member supported by said mount structure and a continuous spacer completely surrounding said member affixed thereto at a plurality of spaced points and restrained by said envelope at a plurality of points each intermediate two of said spaced points.

3. An electron discharge device comprising an envelope having a tubular portion, an electrode assembly within said tubular portion, a transverse member supported by said electrode assembly and a metal strip completely surrounding said transverse member and extending to and abutting said tubular portion at a plurality of spaced points about its periphery, the said strip being affixed to said transverse member at a similar plurality of points each of which intermediate two points of abutment against said tubular portion.

4. An electron discharge device comprising an envelope having a tubular section of predetermined internal diameter, an electrode mount structure within said section, a transverse member supported by said mount structure and a continuous band of metal having a length less than the inner circumference of said tubular section affixed to said transverse member at a plurality of points about its periphery, portions of said band of metal extending to and engaging said tubular portion at a plurality of points intermediate said affixed points.

5. An electron discharge device comprising an

envelope having a predetermined internal diameter, an electrode mount structure within said envelope, a transverse member of smaller diameter than said envelope supported by said electrode structure, a single strip of metal completely surrounding said transverse member and attached thereto at three equally spaced points about the periphery thereof, said strip contacting the inner wall of said envelope and portions of said strip lying between each of said points of support on said transverse member being arcuate-shaped between each of said points of support and the point of contact between said strip and said envelope.

6. An electron discharge device comprising an envelope having a tubular portion, a mount structure within said envelope, a pair of axially spaced transverse members supported by said 5 mount structure, a single strip of metal completely surrounding each of said transverse members attached at a plurality of points thereto and contacting said envelope at other points intermediate said points of attachment, the points 10 of contact with said envelope of one of said metal strips being unaligned in an axial direction with the corresponding points of contact of the other of said metal strips.

DON F. HOLSHouser.
